UNITED STATES PATENT OFFICE

ALONZO ALDRICH, OF BELOIT, WISCONSIN

STUFF PUMP

Application filed April 24, 1924. Serial No. 708,615.

My invention relates to stuff pumps, that is to say, pumps for pumping what is known in the paper making art as "stuff," namely a watery mixture containing a certain amount 5 of paper material, more than is used for making the paper, the "stuff" being diluted before being fed or at the time it is fed to the paper making machine.

One of the objects of the invention is to 10 provide a simple, practical and advantageous construction of stuff pump.

Another object of the invention is to provide a stuff pump which will be very compact and occupy a small amount of space.

15 Other objects of the invention are to provide advantageous features of construction in the pump, as will be more especially pointed out hereafter.

In the accompanying drawings Fig. 1 is 20 a side elevation of a stuff pump embodying my invention;

Fig. 2 is an end elevation of the same;

Figs. 3, 4 and 5, are views of details of construction, Fig. 3 being taken on line 3-3 in 25 Fig. 1, and Fig. 4 being taken on line 4-4 in Fig. 5;

Figs. 6 and 7 are views similar to Figs 1 and 2, respectively, of a modified form of machine; and

30 Figs. 8 and 9 are similar views of a still further modification.

Referring to the drawings, I show a stuff pump having a base member 1 supporting the pump mechanism. A plurality, as for example three, of cylinders 2, 2a and 2b, are mounted on this base 1, and arranged side by side, said cylinders being horizontally disposed. Said cylinders 2, 2a and 2b are provided with reciprocating pistons, 3, 3a and 3b, connected with connecting rods 4-4, which connecting rods 4-4 are driven by cranks spaced 120 degrees apart on a rotary shaft 5.

Below the cylinders 2, 2a and 2b are casings 7, 7a and 7b, respectively, and these casings form chambers for the stuff and are connected with stuff inlets 8-8 by a duct or passage formed by the end portion 9 of the base 1. The casings 7, 7a and 7b are conveniently cast integral with the respective cyl-

inders 2, 2a and 2b, and are open at their upper ends so as to communicate with said cylinders 2, 2a and 2b, permitting the stuff to enter either or both of the inlets 8-8, and flow into the stuff chambers formed by casings 7, 7a and 7b, and thence into the cylinders. The flow of the stuff, however, is controlled by ball valves 10-10 seated on valve seats 11-11 at the base of the several stuff chambers 7, 7a and 7b, said ball valves being 60 guided in their vertical movement by guide ribs or vanes 12-12. For permitting access to the interior or stuff chambers 7, 7a and 7b the same are provided with removable doors 14-14 held in place by handles 15-15 on 65 threaded rods 16-16.

Above the cylinders 2, 2a and 2b are casings 17, 17a and 17b, forming stuff outlet chambers, and these are united by pipes 18 and 18a into a single discharge pipe 19, through which the stuff material is discharged. These stuff outlet chambers 17, 17a and 17b are preferably cast together and are in communication with the respective cylinders, and are provided with ball valves 20-20 controlled by guide vanes or ribs 21-21, and arranged to control the outflow or escape of stuff from the several cylinders with which they are respectively in communication. These stuff outlet chambers are also preferably provided with side doors 22-22 held in position by handles 23-23 on threaded rods 24-24, allowing access to the interior of said chambers for various purposes. The pistons 3, 3a, and 3b work in stuffing boxes 25-25 having packing rings 26-26 controlled by adjustable members 27-27, as best shown in Fig. 5. Said piston rods are further supported and guided by guides 29-29 traveling in guideways 30-30. The guides 29 are secured to the pistons 3-3 by annular members 31 having webs 32 secured by bolts 33 to flanges 34 formed on the ends of the tubular pistons 3. The webs 32 also serve as 95 a medium of connection between the pistons 3-3 and their guides and the piston rods 4-4, said pistons 4 being secured by ball or universal joints to said webs 32-32, the latter preferably being laterally recessed so as 100

to form chambers for oil 36 for lubricating said ball or universal joints.

The guideways 30 are conveniently formed by upper guide members 30a and lower guide strips 30b bolted to the upper members 30a by bolts 30c, the guides 29 having their outer edges interposed and working between members 30a and 30b. The members 30b preferably have their inner ends recessed to form chambers for oil 30d.

Thus it will be seen that in operation the reciprocating pistons 3—3 will draw stuff from the stuff feeding or inlet chambers 7a, 7b and 7c, into the several cylinders, 2, 2a and 2b, this inlet of material into the cylinders being brought about by the suction of the out strokes of the pistons and being permitted by the slight rising of the ball valves 10—10. By the in strokes of the pistons, however, the stuff is crowded so as to depress ball valves 10 and close the inlet orifices and also so as to slightly raise ball valves 20 in stuff outlet chambers 17, 17a and 17b, the stuff flowing into and through these chambers and into and out of the discharge orifice 19. In this way the three cylinders will produce a constant pumping action, causing a continuous discharge of stuff material through the outlet 19 from which it can be taken and discharged in any desired way or to any desired place.

It will be seen that the machine is especially advantageous, the cylinders being horizontally arranged and the stuff inlet and outlet chambers being respectively below and above said cylinders so that the machine is very compact and takes but little floor space, which is particularly advantageous in the present condition of the art where machines of this kind and paper machines generally are being built larger and larger all the time. The pump also has a very efficient action, providing amply for taking care of the stuff with its peculiar nature and consistency, part water and part solid material.

Referring to Figs. 6 and 7, I show a modified form of machine having two of the cylinders adapted for use with one kind of material, and a third cylinder adapted for use with another kind of material. To this end a partition 35 is inserted in the inlet 8 so that two of the cylinders receive stuff from the right hand end of inlet 8, (Fig. 7), and the other cylinder receives stuff from the left hand end of said inlet.

In the machine shown in Figs. 8 and 9, all three cylinders are arranged for use with different kinds of material, the inlet 8 being provided with two partitions 36—36 so that the outside cylinders will receive different kinds of stuff from the opposite ends of said inlet 8, and the middle cylinder will receive a third kind of stuff from another inlet 37 feeding material to the cylinder portion of inlet 8 between partitions 36—36.

It will be understood that changes and modifications may be made without departing from the spirit of the invention.

What I claim is:

1. The combination with a plurality of horizontally arranged stuff pump cylinders with a common operating mechanism, of separate interconnected inlets to some of said cylinders and separate interconnected outlets from the cylinders selectively permitting the operation of some of the cylinders on one kind of material and another cylinder or cylinders on a different kind of material. 70 75

2. The combination with a plurality of horizontally disposed stuff pump cylinders, of an inlet for said cylinders having openings to the different cylinders and partition means in said inlet for supplying one or more of said cylinders from a part of said inlet and another cylinder or cylinders from another part of the inlet. 80 85

3. The combination with a plurality of horizontally disposed stuff pump cylinders, of an inlet for said cylinders having openings to the different cylinders and partition means in said inlet for supplying one or more of said cylinders from a part of said inlet and another cylinder or cylinders from another part of the inlet, and a separate inlet for another cylinder. 90 95

In witness whereof, I hereunto subscribe my name this 8th day of April, A. D., 1924.

ALONZO ALDRICH.
